UNITED STATES PATENT OFFICE.

EARL C. HANSON AND WENDELL L. CARLSON, OF WASHINGTON, DISTRICT OF COLUMBIA.

TERAPEUTIC ELECTRODE.

Application filed November 30, 1920. Serial No. 427,439.

To all whom it may concern:

Be it known that we, EARL C. HANSON and WENDELL L. CARLSON, citizens of the United States, residing at Washington, District of Columbia, have invented certain new and useful Improvements in Therapeutic Electrodes, of which the following is a specification.

Our invention relates to electrotherapeutic apparatus and more particularly to high frequency electrodes for electric treatment of the body.

The object of our invention is to provide a high frequency electrode of extremely simple construction not heretofore attained in the art.

Another object of the invention is to provide a high frequency electrode which is substantially non-destructible either physically or electrically.

A further object of our invention is to provide an electrode which has inherently a low specific heat.

There have been but few radical developments in the art of electrodes for electrotherapeutic purposes. We are familiar with previous constructions in which it was proposed to manufacture electrodes from wood, and from solid glass. In the case of solid glass electrodes, due to the relative high heat conductivity of the material, these electrodes conduct heat rapidly during the electrotherapeutic operation. Electrodes of this type become so hot that their satisfactory operation is enhanced. To obviate this difficulty, electrodes were constructed of the vacuum type having a relatively thin glass walled envelope from which the air was exhausted. By a still later development the glass walled electrode was given an interior conductive coating and while it does not require the vacuum heretofore employed, its construction is nevertheless breakable and conductive of heat.

We have discovered that the dielectric for an electrotherapeutic electrode may be constructed of a base composed of carbolic acid and formaldehyde or a condensation product of a phenolic or cresylic body and formaldehyde known commercially as bakelite, or the like. This material may be readily molded about suitably formed conductive plates in any desired shape of electrotherapeutic instrument. While many of these shapes are quite irregular and complicated,

we have found that bakelite will readily follow various shapes, according to the contour of the body for which the instrument is intended.

Our invention may be more clearly understood by reference to the accompanying drawings which form a part of this specification, in which,

Figure 1 is a sectional view of one form of bakelite electrode;

Figure 2 is a sectional view of another form of bakelite electrode showing its association in circuit with an electrotherapeutic apparatus, and;

Figure 3 shows a further construction of electrode partly in section.

Referring particularly to Figure 1 of the drawings, reference character 1 indicates a conductive plate electrically connected thru conducting rod 2 and screw threaded at 4. About this structure is molded a mass of bakelite 3 and shaped to conform with the contour of the body, the contour of the conductive members and bakelite molding depending upon the uses for which the instrument is intended. This bakelite construction is formed under high pressure and embeds the conducting parts throughout their area. The bakelite is molded over the electrically conducting surface 1, and forms a dielectric between this surface and any grounded body to which the electrode is brought adjacent. The end of the bakelite electrode is suitably capped as at 6 and secured by terminal screw 5 threaded on member 4. The electrode is mounted in handle support 7. This support is suitably slotted at 8 and the resilient portions brought together by adjustable thumb screw 9, which may also serve as a terminal connection from which a lead is taken to a source of high frequency oscillations.

Figure 2 shows a different form of therapeutic electrode in which the mass of bakelite 3 is molded to conform with the contour of conductive members 1 and 2 as indicated at surfaces 10 and 11. This dished form of electrode has many applications and is particularly illustrative of the irregular shapes in which bakelite may be molded. Connection is made thru the conducting rod 2 with a source of high frequency oscillations and the other side of the high frequency system is grounded as at 20. The source of high frequency oscil-

lations may comprise the thermionic vacuum tube apparatus 16 having its plate circuit energized by a generator 17 driven by motor 18. For further details of this type 5 electrotherapeutic apparatus reference is made to our Patent 1,338,812 granted May 4, 1920.

Figure 3 shows another form of therapeutic electrode in which bakelite 15 is 10 molded about the electrically conductive member 12. The electrical conductive surface 12 is connected through conducting rod 14 with terminal 4 of the electrode forming a connection for the high frequency 15 apparatus.

This electrode is readily molded from bakelite and differs radically from the solid glass electrode, the vacuum electrodes and the glass walled non-vacuum electrodes here- 20 fore used. The fact that the electrode is non-breakable under impact to which these instruments are ordinarily subject, gives practically indefinite life to the device as compared to the relatively short life of the 25 previous glass electrodes due to breakage. The break down potential of bakelite is far in excess of voltages employed in electro-therapeutics and the material thus with- stands all potentials employed in this oper- 30 ation. The bakelite being a poor conductor of heat can therefore be used for therapeutic electrodes to better advantage than materials heretofore used.

Having thus described our invention 35 what we claim is:—

1. An electrode of the class described comprising an electrically conducting surface, a terminal rod connected thereto, and a condensation product of a phenolic body 40 and formaldehyde molded about said conducting surface and terminal rod.

2. An electrode of the class described comprising an electrically conducting surface and a phenolic or cresylic condensation

product molded about said surface and 45 shaped to conform to the contour of various portions of the body.

3. An electrode of the class described comprising an electrically conducting surface and a coating of a condensation product 50 of a phenolic body and formaldehyde thereover.

4. An electrode for electrotherapeutics comprising an electrical discharge terminal and a dielectric composition of a phenolic 55 body and formaldehyde thereover.

5. An electrode of the class described comprising an electrically conducting surface formed to correspond with the contour of the body and a condensation product 60 of a phenolic body and formaldehyde molded over said surface and correspondingly shaped in accord with the contour of the body.

6. An electrode of the class described 65 comprising an electrical discharge terminal and a dielectric material of a condensation product of a phenolic body and formalde- hyde softened to surround said terminal and hardened under heat and great pressure to 70 conform with the contour of the body for which said electrode is intended.

7. An electrode of the class described comprising an electrical discharge terminal and a dielectric composition of carbolic acid 75 and formaldehyde molded thereover.

8. An electrode of the class described comprising an electrically conducting surface, a terminal rod connected thereto and a condensation product of a phenolic body and 80 formaldehyde molded about said conduct- ing surface and terminal rod substantially embedding the entire area thereof and a connection at the end of said electrode whereby high frequency energy may be sup- 85 plied to said conducting surface.

EARL C. HANSON.

WENDELL L. CARLSON.
